UNITED STATES PATENT OFFICE.

JAMES S. THOMPSON, OF PELHAM, NEW YORK.

PERMANENT MOLD FOR MAKING CASTINGS.

Application filed August 11, 1924. Serial No. 731,242.

To all whom it may concern:

Be it known that I, JAMES S. THOMPSON, a citizen of the United States, residing at Pelham, in the county of Westchester and State of New York, have invented certain new and useful Improvements in Permanent Molds for Making Castings, of which the following is a specification.

This invention relates to permanent molds for making castings and its object is to facilitate opening and closing the mold and to enable this operation to be quickly and easily accomplished without injury to the casting or to the mold and with the exercise of a minimum amount of labor.

A further and important object of the invention is to provide means whereby one member of a permanent mold may be moved bodily and uniformly away from the other member or members of the mold to clear any projections of the casting in the movable member of the mold so that this movable member can be swung to open position without engaging any part of the casting and without damaging the casting or the mold in any way.

The invention also has for its object to provide means for connecting the members of a permanent mold so that one member can be swung relative to the other member to open position to permit access to the mold cavity or to permit removal of the casting, these means being constructed and arranged to be easily operated in a manner which will enable the movable member of the mold to clear projections on the casting before the swinging movement commences, whereby the movable member can be swung to open position without damaging the casting or the mold.

In the accompanying drawings I have illustrated a selected embodiment of the invention, wherein—

Fig. 1 is a side elevation of a permanent mold embodying the invention.

Fig. 2 is a top plan view.

Fig. 3 is a rear end elevation.

Fig. 4 shows the cope thrown to open position relative to a portion of the drag.

In that embodiment of the invention selected for illustration in the drawings, the permanent mold comprises a drag 5 and a cope 6 having a mold cavity 7 therein adapted for casting a brake shoe. The walls of

the mold cavity may consist in whole or in part of the metal of the drag and the cope, or all or parts of the cavity walls may consist of refractory material set in the drag and cope, or the walls may be provided with a refractory or other coating in whole or in part, as may be desired to produce a plain cast iron casting or a chilled cast iron casting or a cast iron casting part plain and part chilled. In a series of Patents, No. 1,484,421 to 1,484,438 inclusive, granted to me February 19, 1924, I have disclosed certain improvements in and relating to permanent molds which are adapted for making brake shoes and other plain or partly chilled cast iron castings, and while this invention is especially desirable in those molds which have mold cavity walls all or partly refractory, because of the relatively fragile character of the refractory, it is not the less important in molds having cavity walls made entirely of metal because of the great facility afforded by the invention for opening and closing the mold without damage to the casting or to any part of the mold. Therefore, I would have it understood that the present operating mechanism is adaptable for use in any type of permanent mold, so far as I am aware, in which one member must be swung away from the other member or members to permit access to the mold cavity or to the casting.

In my Patents No. 1,484,439 and 1,484,440 granted to me February 19, 1924, I have shown means which have proven to be useful and satisfactory for the purpose of imparting a kick or jar to the cope of a permanent mold to release it from possible sticking contact with the drag and the casting preliminary to the opening operation. The present invention also has for its object to dispense with any "kicking" or other operation preliminary to the opening operation, and to enable the mold to be opened in one continuous operation, wherein the movable member, whether it be the cope or some other part, is given a movement relative to the stationary member or members which will enable the movable member to clear any parts of or projections on the casting before the swinging movement of the opening operation commences. In other words, it is an important object of the invention to impart to the cope a rectilinear movement, that

is to say, in a right line, from the stationary member or members of the mold until the movable member has reached a position where in swinging to open position it will 5 clear all parts of the stationary member or members and of the casting.

The drag is provided at its rear end with lugs 8 and bell crank levers are pivoted at 9 to the lugs 8 with arms 10 projecting up- 10 ward and arms 11 projecting forward from said pivot when the mold is closed (Fig. 1). The arms 11 are provided with slots 12 to receive the pins 13 which are secured in the rear end 14 of the cope, the slots being pro- 15 vided to permit a movement of the cope in a right line away from the drag for a limited distance, while the bell crank levers are swinging in an arc on their pivots 9. The arms 10 are connected by a cross-bar 15 and 20 provided with a short stud 16 to receive a removable handle bar 17 which may be a section of pipe. Parallel links 18 project forward from the bell crank levers to a position adjacent the forward end of the cope, 25 where they are pivotally connected at 19 to the upright arms 20 of bell crank levers, which are pivoted at 21 to the cope. Arms 22 of these bell crank levers project rear- 30 wardly alongside the cope and have rounded bearing surfaces 23 arranged to engage complementary bearings 24 on the plates 25 which are fastened to the drag. Pins 26 are fixed in the cope above the short arms 22 and these pins project only a short dis- 35 tance from the sides of the cope so that they will be engaged by the arms 20 but will be cleared by the links 18.

The mold, as shown, is provided with a removable pouring gate 27 and a gate core 28, which form the end of the mold cavity, 40 as more particularly set forth in my companion application S. N. 731,243 filed con- currently herewith, but the invention is not limited to a permanent mold of particular 45 construction, since it will be apparent that it can be applied to many of the molds of my patents aforesaid, as well as to the particular mold herein shown, and others.

In practice, the hot metal having been 50 poured in the closed mold, force is applied to the levers 16 to swing the cope from closed position, indicated in full lines in Fig. 1, to open position as shown in Fig. 4. The mold shown is made to produce a brake 55 shoe and the mold cavity 7 indicated in broken lines sufficiently shows the shape of the cavity for producing a car shoe having an attaching lug 29 and end lugs 30. It will readily be seen that the cope must be lifted or moved rectilinearly relative to the drag before it is swung bodily endwise in order that the cope may clear the attaching lug and the end lugs and otherwise release itself 60 from the drag and the casting. This brake 65 shoe casting illustrates very clearly the im-

portance, as well as the operation, of the invention, but I do not limit the invention to the manufacture of brake shoes, since it can be employed with satisfactory results in making other castings.

70

Therefore, in order to move the cope bodily away from the drag in a right line to clear the drag and the casting, the slots 12 provide for the necessary lost motion between the rear bell cranks pivoted at 9 and the cope, and the forward bell cranks pivoted at 21 constitute guides whereby when the lever 17 is pulled rearward, to the right in Figs. 1, 2 and 4, the cope moves upward for a distance sufficient to clear the projections on the casting, as indicated in broken lines in Fig. 1, and then begins its swinging movement from this broken line position in Fig. 1 to the position indicated in Fig. 4. This initial rectilinear movement of the cope is induced by the lever 16 through the bell cranks pivoted at 9, and the slots 12 provide that amount of lost motion necessary to enable the bell cranks to swing in an arc on their pivots, while at the same 90 time they are lifting the cope from the drag; and the forward bell cranks pivoted at 21 having a bearing in the seats 24 on the drag operate as guides to compel the cope to move only in a right line for a limited 95 distance sufficient for the cope to clear the projections on the casting before the cope begins its swinging movement to full open position. The initial right line movement and the swinging movement in an arc on the center 9 are successive, but constitute a 100 continuous opening operation.

When the cope has proceeded in its right line movement a sufficient and predetermined distance, the arms 20 of the guide bell crank levers will engage the pins 26, and thereafter the cope is caused to swing in an arc on the center 9. When the cope is fully opened, it may conveniently rest upon the floor 31 and in the construction illustrated the cross-bar 15 engages the floor. The weight of the cope causes it to swing downward on the center 13 and engagement of the pins 26 with the arms 22 of the guide bell crank levers limits this movement of the cope, so that it is maintained in a convenient position, when opened, for the insertion of a reinforcing back and lug, or for any other purpose. To close the mold, the lever is swung forward and the cope is returned to engagement with the drag, as shown in Fig. 1.

The invention comprises a simple and easily manipulated operating mechanism for opening a permanent mold with the exercise of comparatively little power, and without liability of damage to the mold, or to the casting, by imparting to the movable member of the mold an initial movement in a right line relative to the drag, until it clears

all projections on the drag and the casting and is free to swing in an arc endwise to open position. This enables the mold to be opened very shortly after the metal has been 5 poured, so that the casting may cool more rapidly and be removed to permit the mold to be set for another casting operation. The invention overcomes any tendency of the movable member of the mold sticking and 10 avoids liability of damage to the mold or to the casting by reason of sticking or other difficulties which are sometimes experienced in opening permanent molds.

The invention can be applied to molds of 15 different construction and for that, and other purposes, various changes in the form, construction and arrangement of parts may be made without departing from the invention or sacrificing its advantages, and I consider myself entitled to make all such 20 changes as fairly fall within the scope of the following claims:

I claim:

1. The combination of a permanent mold 25 comprising a movable member and a relatively fixed member, a lever for operating the movable member, and means for imparting to the movable member an initial rectilinear movement relative to the fixed member followed by a swinging movement to 30 open the mold.

2. The combination of a permanent mold comprising a movable member and a relatively fixed member, a lever pivotally engaged with the fixed member for swinging the movable member to open position, and means cooperating with said lever for imparting to the movable member an initial rectilinear movement relative to the fixed member before the movable member swings on the pivot of the lever as a center to open 40 the mold.

3. The combination of a permanent mold comprising a movable member and a relatively fixed member, a lever pivoted to the rear end of the fixed member and engaged with the rear end of the movable member, and means cooperating with the lever for imparting to the movable member an initial rectilinear movement relative to the fixed member before the movable member swings on the pivot of the lever as a center to open 50 the mold.

4. The combination of a permanent mold 55 comprising a movable member and a relatively fixed member, a lever engaged with one end of the fixed member and with the corresponding end of the movable member for swinging the movable member to open position, and means at the other end of said members to guide the movable member in a rectilinear movement relative to the fixed member before the movable member is 60 swung to open position.

5. The combination of a permanent mold 65

comprising a movable member and a relatively fixed member, a lever pivoted to the rear end of the fixed member and loosely engaged with the rear end of the movable member for operating the movable member, 70 and guiding means on said members for imparting to the movable member an initial rectilinear movement relative to the fixed member before the movable member swings on the pivot of the lever as a center to open 75 the mold.

6. The combination of a permanent mold comprising a movable member and a relatively fixed member, a lever for operating the movable member and engaged therewith, means for providing lost motion between said lever and said movable member to permit limited independent movement of each, and guiding means for compelling an initial rectilinear movement of the movable 85 member relative to the fixed member before the movable member swings to open position.

7. The combination of a permanent mold comprising a movable member and a relatively fixed member, a lever pivoted at one end of the fixed member and loosely engaged with the corresponding end of the movable member for operating the movable member, and guiding means comprising a 90 lever on the movable member having a bearing on the fixed member for compelling an initial rectilinear movement of the movable member relative to the fixed member before the movable member swings to open position.

8. The combination of a permanent mold comprising a movable member and a relatively fixed member, a bell crank lever pivoted to one end of the fixed member and having one arm thereof loosely engaged with the corresponding end of the movable member, a bell crank guide on the movable member at its other end, a bearing on the fixed member for one arm of the guide, and links connecting the other arms of said lever and guide to compel an initial rectilinear movement of the movable member relative to the fixed member before the movable member swings to open position.

9. The combination of a permanent mold comprising a movable member and a relatively fixed member, a lever for operating the movable member, said lever being pivoted to the fixed member and loosely engaged with the movable member to permit lost motion between the lever and the movable member, a guide on the movable member having a bearing on the fixed member, and means for connecting the lever and the guide so that the movable member has an initial rectilinear movement relative to the fixed member before the movable member swings to open position.

10. The combination of a permanent mold 130

4
comprising a movable member and a relatively fixed member, a bell crank lever pivoted to the rear end of the fixed member and pivotally connected to the rear end of the movable member to provide a lost motion between itself and the removable member, a bell crank guide pivoted to the movable member adjacent its forward end and having a bearing on the fixed member, links 10 connecting the lever and the guide, and a stop on the movable member for limiting the movement of the guide whereby to impart to the movable member an initial rectilinear movement relative to the fixed member followed by swinging movement of the mov- 15

able member on the pivot of the lever as a center to open the mold.

11. The combination of a permanent mold comprising a movable member and a relatively fixed member, a removable pouring gate and a sand core therefor arranged to form one end of the mold cavity, a lever at the opposite end of the mold for operating the movable member, and means for imparting to the movable member an initial rectilinear movement relative to the fixed member followed by swinging movement to open the mold. 20 25

JAMES S. THOMPSON.
